UNITED STATES PATENT OFFICE.

PAUL FLEMMING COX, OF CHICAGO, ILLINOIS.

ADDRESSING MACHINE.

Application filed January 19, 1925. Serial No. 3,403.

To all whom it may concern:

Be it known that I, PAUL F. Cox, a citizen of the United States, residing at Chicago, in the county of Cook and State of Illinois, have invented certain new and useful Improvements in Addressing Machines; and I hereby declare that the following is a full, clear, and exact description thereof, reference being had to the accompanying 10 drawings, which form part of this specification.

This invention is an improvement in addressing machines. The invention provides a rotary galley addressing machine having 15 a plurality of circumferentially disposed rows of spaced spring clips on the periphery of the galley adapted to receive address slugs of one, two, three or more lines, each operation of the machine advancing the galley one slug space regardless of the number 20 of lines therein; also an addressing machine in which the rotary galley is readily removable and replaceable as a unit, means being provided to remove and replace the galley, and for supporting the galley when so 25 removed in rotatable position; also a hinged feed board adapted to be swung aside to permit removal of the galley, said feed board having a transparent panel 30 therein whereby the slugs may be inspected before reaching the printing point; also means for taking a galley proof or impression from all the slugs. The machine may be operated by foot or power as desired; 35 and means are provided for inking the slugs, and advancing the galley one slug space, for each operation of the machine. Other features of the invention will be hereinafter set forth.

40 I will explain the invention with reference to the accompanying drawings, and summarize in the claims the novel features of construction and novel combinations of parts for all of which protection is desired.

45 In the drawings:

Figure 1 is a side elevation of the complete addressing machine.

Figure 2 is an elevation of the opposite side, showing the motor power attachments.

50 Figure 3 is a side elevation, similar to Fig. 2, showing the rotary galley removed from the machine and the feed board raised.

Figure 4 is a perspective view of the galley truck, detached.

55 Figure 5 is a front end elevation of the

machine, showing in dotted lines the crank used for rotating the galley when inking or taking a proof impression of the slugs.

Figure 6 is an enlarged detail of the galley showing one, two, and three address 60 slugs secured in the clips.

Figure 7 is a top view of the address slug clips, shown in Figure 6.

Figures 8 and 9 are enlarged detail views 65 of the means for rotating the galley.

Figure 10 is an enlarged detail view of the galley stop devices.

Figure 11 is an enlarged detail view of the means for preventing backward rotation 70 of the galley.

Figure 12 is an enlarged detail section on the line 12-12, Figure 7.

Figures 13 and 14 are enlarged detail views 75 of the means for disconnecting the sections of the connecting rods when the machines are power driven.

Figure 15 is an enlarged longitudinal section through the platen showing the means for adjusting the rubber block.

Figure 16 is an end elevation of the 80 platen.

The machine comprises parallel side frames 1, which are preferably of same size and shape, and are suitably spaced apart by tie-rods 1^a, or the like, at the bottom, top, and one end of said frames.

85 The side frames 1 are provided with open bearings 1^b, adapted to receive the shaft 2^a of the rotary galley 2, said bearings 1^b being so formed that shaft 2^a carrying the galley 2 may be readily lifted out of or replaced in same, as hereinafter described.

90 The galley 2 preferably comprises opposite wheels 2^b, preferably made of cast iron, and a sheet metal cylinder 2^c is secured to and between the peripheries of the wheels forming a circular drum upon the periphery of which the address slugs S are retained, as hereinafter described. The said galley is 95 mounted upon a shaft 2^a, which shaft extends somewhat beyond the side frames, 1, 1', when journaled in the bearings 1^b, 1^b as shown in Fig. 5.

100 To the periphery of the cylinder 2^c are secured a plurality of transversely disposed slug-holding spring clips 3, said clips being arranged in a plurality of circumferentially disposed rows (five such rows being shown in Fig. 5). Each wheel 2^b has an annular 105 series of ratchet teeth 2^b' on its outer face 110

adjacent its periphery and the number of clips 3 in each row is made equal to the number of teeth in the annular ratchets, and as the address slugs S are interposed between 5 adjacent clips 3 in each galley the movement of the galley one tooth space, as hereinafter described, will advance the same one slug space. In actual practice, by the above arrangement a galley drum of thirty-two 10 inches diameter, having five rows of clips 3 with two hundred clips in each row, would provide places for 1000 address slugs S. Obviously by changing the diameter or length of galley 2 the capacity of the galley 15 will be accordingly varied.

As shown in Figures 6, and 7, each clip 3 is preferably formed of a strip of sheet metal, extending the full length of the drum, and has a longitudinal base portion 3^a secured to the sheet metal cylinder 2^c, preferably by means of tongues 3^{a'} (Figs. 7 and 12) partly punched from the base 3^a and passing through slots 2^{c'} in the cylinder 2^c, said tongues being bent in opposite directions to lock the clips to the cylinder. At 20 side of base 3^a is a shallow upturned flange 3^b, and at the other edge of base 3^a is an upwardly extending flange 3^c, somewhat less in height than the slugs S. Flange 3^c is 25 preferably inclined slightly away from the flange 3^b, and from the outer edge of flange 3^c extend a plurality of spring fingers 3^d, which are bent inwardly almost parallel 30 with flange 3^c, said fingers being preferably arranged in pairs, as shown in Figure 7. Each pair of fingers 3^d is adapted to engage 35 a slug S, inserted between said fingers and the flange 3^c of the next adjacent clip 3, see Fig. 6.

40 The clips 3 are mounted on cylinder 2^c with the flange 3^c of one clip abutting against the flange 3^b of the next adjacent clip (Fig. 6) and the address slugs S are placed in the grooves formed by and between the flanges 3^c and fingers 3^d of adjacent clips 3, and will be securely retained in place by said fingers, and will not fall out when the galley is rotated. Each finger 45 3^d is preferably bent as shown in Fig. 6, so as to have two points of contact with the slug. In the galley shown, each clip 3 is provided with five pairs of fingers 3^d; and there are five circumferentially disposed rows of spring fingers (see Figure 5); and 50 each rotative movement of the galley one ratchet tooth will advance the galley one slug space.

As shown in Fig. 6, the clips 3 constructed 60 and arranged as described are adapted to securely retain either slugs of different thickness—say a one line, two line, or even three line slug—thereby permitting the use of different thicknesses of address slugs, bars, or point thickness type. Each slug is 65 securely but removably held in place with-

out danger of dropping or falling out of the galley, and the mixed use of one, two or three line slugs does not affect the relation of the clips 3 and the ratchet teeth of the galley drum.

70 Mounted in bearings 1^c, at the tops of the side frames 1, towards the rear end of the machine, is a shaft 5^a upon which is pivoted a platen frame comprising parallel arms 5^b, suitably spaced apart by tie-rods, said frame 75 carrying at its forward end a cross bar 5^c upon which is slidably and adjustably mounted a platen 5, adapted to successively press papers, envelopes, or other articles to be addressed, against the inked address slugs 80 S, in each row as the galley is advanced step by step.

The galley 2 is advanced one ratchet tooth for each operation of the machine by suitable means. As shown a foot pedal 4 is pivoted upon the frames 1, and normally held in elevated position by means of springs 4^a connected to said pedal and to said frames. Rods 4^b connect pedal 4 with the arms 5^b, of the platen frame, so that 85 each depression of the pedal will depress the platen 5 and press an article to be addressed against the inked address slugs. One arm 5^b, has an extension 5^d projecting to the rear of the shaft 5^a, and as the platen frame 90 is raised, extension 5^d is lowered and vice versa.

95 Pivoted on the adjacent tie rod 1^a is a link 6 having a head 6^b on its free end provided with a bore 6^c adapted to receive a stud 5^e 100 on a ratchet link 5^f, which is pivotally connected at its upper end to the extension 5^d. The lower extremity of link 5^f (see Figures 8 and 9) is bent as at 5^g, to engage the ratchet teeth 2^b of the adjacent wheel 2 and 105 will, rotatively advance the galley 2 the distance of one tooth on each upward movement of the platen frame. A spring 6^a in bore 6^c engages stud 5^e and presses the tooth 5^g of link 5^f into engagement with the ratchet teeth, but permits the tooth 5^g to slide over the ratchet teeth on each up-stroke of said link. By this construction on each 110 down-stroke of the ratchet link 5^f the galley 2 will be rotated a distance equal to one tooth, and thus the address slugs S are successively advanced to printing position regardless of the number of lines in said slugs.

115 The platen 5, (as shown in Fig. 15) preferably comprises a block 5^s having a bore 5^t through which passes the rod 5^e of the hammer frame, said block being slidably mounted on rod 5^e and retained in adjusted position by a set screw 5^m. In the under 120 side of block 5 is a longitudinal slot 5ⁿ in which is a rubber strip 5^p, which may be adjusted to or from the rod 5^e by means of opposite overlapping wedges 5^q interposed between the strip 5^p and the base of slot 5ⁿ. The outer end of each wedge 5^q is upturned 125 130

as at 5^a, and screws 5^s are rotatably mounted on said ends 5^r and tapped into block 5^s and by adjusting screws 5^s the wedges 5^a can be moved to adjust the rubber strip 5^r to adjust the impression pressure excited by the platen.

A suitable "stop" device is provided to prevent excess movement of the galley at each advance thereof. As shown a pawl 7 (Figure 10) is pivotally mounted on a bracket 7^s on one side frame of the machine, adjacent the connecting rod 4^b and opposite the ratchet teeth 2^b of the other wheel of the galley. One end of pawl 7 is normally held in engagement with the ratchet teeth by a spring 7^a. The other end of pawl 7 projects beside the connecting rod 4^b and is adapted to be engaged by a wedge or cam 7^b mounted on the rod 4^b, whereby in such position that on each upstroke of the connecting rod 4^b (as the galley 2 is being moved by link 5^r) the cam 7^b will engage the adjacent end of pawl 7 and force the pawl out of engagement with the ratchet teeth, and permit the galley 2 to be rotated one tooth by link 5^r; and the further movement of rod 4^b the cam 7^b will permit spring 7^a to force the pawl again into engagement with the teeth, thereby preventing rotation of the galley more than a single tooth space when the drum is being advanced by the link 5^r.

Suitable means are provided for preventing backward movement of the galley 2 after each forward movement in case the galley should be unbalanced due to the fact that slugs S are not always evenly distributed over the periphery of the galley 2. As shown in Figure 11 a set of pawls 8 (three being shown) are pivoted on one side frame of the machine, and are normally urged into contact with the adjacent ratchet teeth 2^b by springs 8^a. The pawls in the set are preferably set at slightly different relative positions to ensure that the galley will not "back up" or advance too far at each operation.

A feed table 9 is hingedly mounted as at 9^a, upon one of the side frames, and is normally supported in horizontal position by the opposite side frame. The table 9 can be swung upwardly, as shown in Figure 3, to permit the galley 2 to be withdrawn from or replaced in the machine as hereinafter described. A bar 9^b is mounted on the side frames adjacent the rear edge of table 9 when the latter is lowered and is adapted to support the rear end of newspapers, periodicals, and the like when being impressed. When platen 5 is depressed the articles to be addressed are forced against the inked address slugs S at that moment positioned between the bar 9^b and the adjacent edge of table 9.

Preferably the table 9 is provided with a sight opening covered by a transparent

plate 9^c (Figure 3) so that the operator may visually inspect the address slugs as the galley 2 advances them toward the printing point.

Suitable means for inking the slugs S is provided. As shown an ink plate 10 is preferably pivotally mounted on the frame as at 10^a for convenience in shipping, and is normally supported in horizontal position by braces 10^b. A hand inking collar 10^c is journaled in open bearings 1^c, in the side frames 1 adjacent the inner end of plate 10.

When the machine is to be used the roller 10^c is inked by manually removing same from its journals 1^c, and rolling it on the ink plate 10. Then the roller is replaced in the journals 1^c and in such position it applies ink to the address slugs S, as the galley 2 is rotated, preferably by the use of a crank 2^b, shown in dotted lines in Fig. 5, which crank is removably mounted on one end of the galley shaft 2^a.

Means are provided for taking a proof of all the slugs S on a continuous sheet; said means comprising a roll of paper 11 mounted on a shaft 11^a journaled in the upper end of a rocking frame 11^c pivotally mounted at 11^b on the side frames 1 (see Figs. 1-3). An impression roller 11^b is journaled in the lower end of the frame 11^c and by swinging the frame 11^c the roller 11^b may be swung toward or from the slugs S. The web of paper is passed from roll 11 between the roller 11^b and the slugs S on the galley 2, and the roller 11^b moved in to press the web into contact with the slugs and then as the galley is rotated, (as by means of crank 2^b, Fig. 5) an impression will be taken on the web from all of the slugs S. Roller 11^b preferably extends the full width of the galley 2. The frame 11^c is normally positioned to hold the roller out of contact with the slugs except when a galley proof is to be taken.

The machine may be operated by foot or power. When operated by power the rods 4^b should be disconnected or rendered ineffective. As shown an electric motor 12 mounted in the frame is belted to a pulley 12^a on a shaft 12^b journaled in one of the side frames, and a bracket 12^c attached to said side frame. On shaft 12^b is mounted an eccentric 12^d, and the eccentric strap is connected by rod 12^e to fit a stub 5^w on the platen frame and is removably retained thereon by a nut 5^v. Eccentric 12^d can be engaged with shaft 12^b by a suitable clutch as 12^f controlled by the operator. As shown the suitable clutch member is operated by a bell crank 12^g connected by a rod 12^h to the foot pedal 14 of the machine; and when the pedal is depressed the clutch is engaged and the rod 12^g caused to operate the platen 5.

When the machine is manually operated

the eccentric rod 12^a is disconnected from the platen frame and the trip rod 12^b disconnected from pedal 4. The machine will then operate as a foot machine only, through 5 the pedal 4 and connecting rods 4^b. When it is desired to operate the machine as a power machine, the eccentric rod 12^a must be connected with the hammer frame 2^b and the trip rod 12^b connected to pedal 4 10 and the rods 4^b disconnected. As shown in Figs. 13 and 14, the rods 4^b may be made in two sections each having overlapped portions 4^x at their meeting ends. One portion 4^x has two slots 4^w in one side respectively 15 adapted to receive a stud 4^y and a thumb nut 4^z extending from the other portion. When thumb nut 4^z is loosened the sections may be readily disengaged, to permit the machine to be operated as a power driven 20 machine.

For removing and replacing galleys in the machine a galley truck is provided. As shown in Figures 3 and 4 the truck comprising a U-frame 13, supported on 13^a, the 25 parallel legs of said U-frame being spaced apart a distance slightly greater than the overall width of the machine. Upon the base 13 are upright standards 13^b, of desired height, and a forked lever 13^c is 30 pivotally mounted on said standards. In the outer ends of the forked lever are open sockets 13^e adapted to receive the ends of the galley shaft 2^a. When it is desired to remove or replace a galley, the truck is 35 moved up to the machine and positioned so that the sockets 13^e in the lever 13^c are directly below the ends of galley shaft 2^a. Table 9 having been swung upwardly, as shown in Figure 3, then the forked lever 13^c 40 is depressed, as shown in Figure 4, to lift the galley and shaft 2^a out its bearings 1^b, and the galley can then be removed by withdrawing the truck as shown in Fig. 3. The galley can be replaced by reversing the 45 steps performed in removing it.

I claim:

1. In an addressing machine a frame having open bearings for a rotatable galley; and a rotatable galley carrying a peripheral 50 series of address slugs removably journaled in said bearings and bodily removable from and replaceable in the said bearings.
2. In an addressing machine a frame having open bearings for a rotatable galley; 55 a rotatable galley carrying a peripheral series of address slugs removably journaled in said bearings and bodily removable from and replaceable in the said bearings, and a feed board mounted on the frame above 60 the galley when the latter is in position on the frame, said board being movable to permit the removal or replacement of the galley.
3. In an addressing machine a pair of 65 parallel side frames each having an open bearing; a rotatable galley having a shaft

adapted to be mounted in said bearings, and bodily removable from or replaceable in the bearings and provided with slug retaining devices on its periphery; a feed board mounted on the frame above the galley; a platen mounted on the frame above the galley; means for imparting a step by step rotation to the galley when in the machine; and means for actuating the platen for each step movement of the galley, substantially 75 as described.

4. In an addressing machine, a rotatable cylinder galley; and yieldable clips on the periphery of the galley for retaining address 80 slugs of different thicknesses thereon.

5. In an addressing machine, a rotatable cylindric galley drum and a plurality of rows of yieldable clips on the periphery of the galley for retaining address slugs of various thicknesses thereon.

6. In an addressing machine, a rotatable cylindric galley, and a plurality of rows of parallel transverse spring clips mounted upon the periphery of the galley for retaining address slugs of different thicknesses 90 thereon.

7. In an addressing machine, a galley, and spaced clips mounted upon the galley for retaining address slugs, each clip having opposite shallow and high flanges and curved 95 spacing fingers, the fingers of one clip co-operating with the high flange of the next adjacent clip to hold a slug.

8. In an addressing machine, a rotatable cylindric galley having a plurality of parallel spaced clips mounted upon its periphery for retaining address slugs, each clip comprising a base and integral opposite shallow and high flanges at opposite sides of the base 105 and curved spacing fingers on the higher flange, the fingers on one flange cooperating with the high flange of the next adjacent clip to hold a slug.

9. In an addressing machine, a rotatable cylindric galley having ratchet teeth and spaced spring clips mounted on the periphery of said galley parallel to the axis thereof, each clip being disposed opposite a ratchet tooth; said clips being adapted to 110 retain address slugs inserted between adjacent clips; an impression member; and means for moving the galley one tooth for each actuation of the impression member.

10. In an addressing machine the combination of a supporting frame; a cylindric galley mounted therein and having spring clips on its periphery for the retention of address slugs; and an annular ratchet on each end; a table mounted on the frame; an oscillating platen mounted on the main frame adapted to coact with the slugs; a reciprocatory pawl adapted to engage one of the annular ratchets to impart a step by step motion to the galley; means for reciprocating said pawl; and a pawl engaging 125

the other ratchet to prevent backward rotation of the galley.

11. In mechanism as set forth a galley, a platen and means for operating the platen comprising a rotatable shaft; an eccentric loosely mounted thereon; a link connecting the eccentric strap with the platen; and manually controlled clutch mechanism whereby the eccentric may be caused to turn with the shaft.

12. In combination with mechanism as set forth in claim 11 means to prevent excess movement of the galley at each forward movement thereof.

13. In an addressing machine the combination of a supporting frame; a cylindric galley mounted therein having spring clips on its periphery for the retention of address slugs and having an annular ratchet on each end; a feed table mounted on the frame; a bar mounted on the frame adjacent the table to assist in supporting the mail matter during the impressions; an oscillating platen adapted to coact with the slugs, a reciprocating pawl adapted to engage one of the annular ratchets to impart a step by step motion to the galley; means for reciprocating said pawl; and a pawl engaging the other ratchet to prevent backward rotation of the galley.

14. In mechanism as set forth in claim 13, means for operating the platen comprising a rotatable shaft; an eccentric loosely mounted thereon, a link connecting the eccentric strap with the platen, and manually controlled clutch mechanism whereby the eccentric may be caused to turn with the shaft.

15. In combination with mechanism as set forth in claim 13 means to prevent excess movement of the galley at each forward movement thereof.

16. In combination with mechanism as set forth in claim 13 a set of pawls adapted to engage the ratchet and prevent excess movement of the galley at each forward movement thereof.

17. An addressing machine comprising a frame; a rotatable galley carrying address slugs mounted in said frame; a platen adapted to take an impression from said slugs; means for advancing the galley one slug space for each actuation of said platen, and means for operating the platen comprising a rotatable shaft; an eccentric loosely mounted thereon, a link connecting the eccentric strap with the platen; means for driving the shaft, and manually controlled clutch mechanism whereby the eccentric may be caused to turn with the shaft.

18. An addressing machine comprising a frame; a rotatable galley carrying address slugs mounted in said frame; a platen adapted to take an impression from said slugs; means for advancing the galley one slug space for each actuation of said platen,

means for operating the platen comprising a rotatable shaft; an eccentric loosely mounted thereon; a link connecting the eccentric strap with the platen; means for continuously driving the shaft of a manually controlled clutch mechanism whereby the eccentric may be caused to turn with the shaft; and means to prevent excess movement of the galley at each forward movement thereof.

19. In an addressing machine, a pair of side frames having oppositely disposed open bearings in said frames; a shaft in said bearings; and a galley on said shaft; said shaft being liftable out of said bearings to remove the galley from or replace the galley in the machine.

20. In a machine as set forth galley advancing means comprising ratchets on said galley each having a tooth opposite each address slug; a pivoted member having its outer end overlying said ratchet teeth; a stud on said member adjacent its lower end; a link pivoted on the frame and having a recess for the reception of said stud, and a spring in said recess engaging said stud for normally urging the member into contact with said teeth; whereby each actuation of the arm will operate said member to advance the drum one ratchet tooth.

21. In a machine as set forth in claim 20, a plurality of pawls yieldably engaging said ratchet teeth, said pawls being spaced apart a distance slightly greater than the spacing of the ratchet teeth, whereby backward rotation of the drum will be prevented.

22. In a machine as set forth a galley carrying slugs; and means for taking a galley proof, comprising a paper roll support pivoted on the main frame; an impression roller mounted on said support, and adapted to be moved into or out of contact with the slugs; the web of paper passing between said roller and galley, whereby as the drum is rotated an impression is taken on said web.

23. An addressing machine comprising a frame, a rotatable galley drum carrying a plurality of rows of address slugs mounted in said frame; an arm pivoted on said frame; a platen on said arm adapted to contact with said slugs; means for actuating said arm; means for advancing the drum one slug space for each actuation of said arm; means for inking the slugs; and means for taking a galley proof from said slugs.

24. In a machine as set forth a platen comprising a block having a slot, a platen strip in said slot; opposed slideable wedges interposed between said strip and the base of said slot; and means for adjusting the wedges to adjust the contact strip.

25. In a machine as set forth platen actuating means comprising a driven shaft journaled in the frame; an eccentric loosely

mounted on said shaft; a clutch for locking the eccentric to the shaft; a rod connecting the eccentric strap with the platen; a pedal; and a trip rod connecting said pedal for 5 operating the clutch.

26. An addressing machine comprising a frame, a rotatable galley carrying a plurality of rows of address slugs mounted in said frame; a member pivoted on said 10 frame; a platen on said member adapted to coact with said slugs in taking an impres-

sion; means for actuating said platen; means for advancing the galley one slug space for each operation of said platen; means for preventing excess rotation of the galley at each forward movement thereof; means for preventing backward rotation of the galley; and means for inking the slugs.

In testimony that I claim the foregoing as my own, I affix my signature.

PAUL FLEMMING COX.
